UNITED STATES PATENT OFFICE.

NELSON B. HENRY, OF ATLANTA, GEORGIA, ASSIGNOR TO THE MURRAY COMPANY,
OF DALLAS, TEXAS, A CORPORATION OF TEXAS.

PUMP FOR HYDRAULIC PRESSES.

1,377,248.

Specification of Letters Patent. Patented May 10, 1921.

Application filed August 23, 1920. Serial No. 405,461.

To all whom it may concern:

Be it known that I, NELSON B. HENRY, a citizen of the United States, residing at Atlanta, in the county of Fulton and State 5 of Georgia, have invented certain new and useful Improvements in Pumps for Hydraulic Presses, of which the following is a specification.

My invention is an improvement in pumps 10 for hydraulic presses.

In the pressing of oil seed or analogous material in a hydraulic press, to extract therefrom the maximum amount of oil or fluid, it is desirable to apply the pressure 15 gradually in order that the oil expressed from the seed mass, as the pressure becomes effective, may have ample time to find its way to the surface and leave the mass. If the maximum pressure to be applied is, for 20 example, four thousand pounds per square inch, an initial pressure of say two thousand pounds will be reached in a comparatively short time, in an ordinary oil press in about four minutes. But this ratio of time and pressure 25 cannot be maintained in applying the additional pressure desired, for the obvious reason, that, as the material operated upon becomes more dense, it is necessary to allow a certain time for the expressed oil to find 30 its way out of the mass and as the density is increased, by gradual increase of pressure, to the maximum, it is desirable that the press plunger should be moved more and more slowly until the full pressure is applied 35 and substantially all the oil has been expressed.

At about midway of the pressing operation, say about 2000 pounds pressure, the seed mass has become dense, all air having 40 been extruded from the mass and the seeds forced into intimate contact and the extrusion of oil proceeds rapidly with the result that the bulk of the mass shrinks by the amount of oil that passes out of the mass. 45 This shrinkage of mass tends to relieve pressure and is immediately counteracted by the movement of the press plunger which takes up the shrinkage and continuing its movement, applies a further increment of pressure 50 sure to the mass, producing an additional oil extrusion. This process of pressure, partial collapse of the mass tending to relieve pressure and the take up of the shrinkage and establishment of an additional pressure 55 continues until the maximum pressure has

been attained and maintained for a sufficient time, when the seed mass has become very solid and no further oil extrusion is practically possible.

As the pressure in the hydraulic press is 60 increased and the seed mass becomes more dense it is obvious that it will require a continuously increasing power to force a given amount of fluid from the pump to the press in a given time or, in the alternative, that 65 the amount of fluid forced into the press in a given time shall be decreased as the resistance becomes greater. This effect has been attained heretofore by actuating the piston of the hydraulic pump, through a 70 stiff spring, which as the resistance to the movement of the piston increased, yielded more and more and, in this way, the stroke of the piston was progressively shortened and less fluid ejected from the pump cylinder 75 as the piston was reciprocated at a regular power and speed. In this pump, however, at each stroke of the piston the piston spring was compressed and released, causing irregularity of action and a waste of 80 power.

In my present invention I design to drive my hydraulic pump at a uniform speed and positively and, as the resistance to the pumping action increases, as the pressure in the 85 press increases, to provide a regularly increasing space by means of an auxiliary cylinder and piston to receive a regularly increasing portion of the charge moved by each reciprocation of the positively driven 90 pump, the difference between the charge moved at each reciprocation of the piston and the variably increasing space of the auxiliary cylinder being the amount of fluid that is forced into the press, which amount is progressively and regularly smaller in proportion to the ever increasing density of the compressed mass, and its consequent lessened shrinkage under increasing pressure. This 95 regularly decreasing proportion of the total 100 charge always moved by the pump piston is accentuated by the fact that the auxiliary piston is preferably controlled by a spiral spring and thus moves a distance exactly proportional to the pressure applied, in the 105 manner of a spring balance, while the seed mass shrinks in volume more and more slowly as the pressure is increased.

I design further to connect the pistons of two pairs of cylinders, the pumping pistons 110

of each pair being coupled together and moving synchronously but in opposite cycles, that is, one pumping piston drawing in a charge of fluid, while the other pumping piston is compressing. The auxiliary pistons of the two pairs will also be connected through the medium of a single compression spring, held between suitable abutments on each piston rod so that the pressure upon one piston will be immediately transmitted through the elastic medium of the spring, to the other piston.

In the drawings, Figure 1 is a top or plan view of a pump for hydraulic presses, embodying my improvement, and Fig. 2 is a longitudinal sectional elevation on line 2-2 of Fig. 1.

Referring to the drawings showing the preferred form of my pump, 1 and 2 are cylinder casings, mounted upon a frame work or base, 3, so as to have the bores or cylinder chambers in axial alignment. The casings 1 and 2 are each bored at each end to form cylinders 4 and 14 and in each casing the inner ends of the cylinders 4 and 14 are connected by a passage 15, eduction and induction passages 12 and 13 being connected to passage 15, with suitable check valves in the well known manner. The several cylinders are provided with suitable glands or stuffing boxes, 5, 7 and 17. Cylinders 4 are provided with pistons 6 and 8 and cylinders 14 with pistons 16. Pistons 6 and 8 are connected at their outer ends with cross-heads 9, these cross-heads being in turn connected together by straps 10 and one of the cross-heads being connected by a pitman 11 with an eccentric 111 mounted upon an actuating shaft 112, carried at one end of the frame 3, and cross-wise thereof. The outer end of each piston 16 is screw threaded and these outer ends carry heads 18 which engage and slide upon a guideway 19 formed on the frame 3. Between the heads 18 is interposed a compression spring 20 which may be compressed as desired by means of nuts 21 mounted upon the screw threaded portion of pistons 16. By movement of one or both nuts 21 the initial tension of the spring 20 may be governed.

The operation of the pump is as follows: Starting at zero pressure the two pumps 6 and 8, moving together but in opposite cycles, alternately force the fluid to a press or presses connected thereto by the eduction ducts 12. During the initial stage of operation, the resistance being relatively small, each piston 6 and 8 displaces its full volume of fluid and forces it to the press, the spring 20 holding the piston 16 without movement. When the pressure in the press and the consequent resistance to the injection of fluid by the pumps 6 and 8 has reached a certain stage (determined by the initial set or com-

pression applied to spring 20 by means of nuts 21) the pressure of fluid as the pistons 6 and 8 move inwardly, begins to take effect upon the pistons 16 and causes a slight yielding of the pistons 16 alternately and as the pressure in the pumps increases so does the movement of pistons 16 and spring 20. It will be seen that when pistons 16 move in their cylinders they provide additional room for a certain portion of the fluid set in motion and displaced by the pistons 6 and 8 and that by this movement of pistons 16 the amount of fluid forced to the press by the movement of pistons 6 and 8 will be lessened progressively as the pressure increases, so that when a pre-determined maximum pressure has been reached, determined by the initial adjustment of spring 20, the pistons 16 in their movement, will provide space for the entire amount of fluid displaced by pistons 6 and 8, so that none of the fluid will be discharged to the press or presses.

This state will continue until a certain amount of the contained oil is extruded, thus relieving the pressure slightly whereupon the balance will be slightly altered and piston 16 will move inward slightly thus causing a small quantity of fluid to be forced to the press and reinstating maximum pressure. When the maximum pressure stands for a reasonable time without any further compression of the seed mass, the seed mass is completely expressed.

When the maximum pressure is reached and no fluid is being forced to the press or presses, the action of the duplex pump is as follows: Piston 6 enters its cylinder 4 on the compression stroke when piston 8 is moving outward in its cylinder 4 on the suction stroke. The piston 16 of the casing 2 is forced to the right under pressure of the fluid displaced by piston 6 and the left hand head 18 is thus forced to the right. At the same instant and to the same extent the piston 16 of the casing 1 moves inward, forced by the movement of piston 16 of casing 2 transmitted through the compressed spring 20. When piston 6 is drawn out on its suction stroke the piston 8 is forced in on its compression stroke and the two heads 18 and spring 20 move in unison with it. The spring thus reciprocates back and forth always under predetermined compression so long as the maximum pressure is maintained, no power being consumed in recompressing a spring which has been permitted to expand and with absolutely regular action. Should a variation in pressure occur in either cylinder 4, as by reason of the extrusion of oil or leakage or defective valves in any of the compression cavities, the spring 20 will take up and rectify the variation by forcing a piston 16 inward toward the cylinder in which the pressure is defective.

- The heads 18 with spring 20 constitute, with the pistons 16 in cylinders 14, a means for controlling the pressure in cylinders 4 by a regular and progressive increase to a 5 predetermined maximum and thereafter the compressed spring 20 without relative movement of its parts will maintain the predetermined pressure by the exact balance of all elements, while in case of leaks or the like 10 disturbing factors the spring 20 and associated parts will automatically and instantly compensate, automatically rectifying and balancing a variation in pressure in either or both cylinders 4, instantly and perfectly. 15 As already stated, spring 20 when once compressed to the predetermined amount, will not normally expand or contract but will simply move bodily with the heads 18 and pistons 16.
- 20 I claim as my invention:
1. In a hydraulic pump, the combination of two pairs of cylinders, each cylinder of a pair communicating at its inner end with its mate and with an inlet and outlet valve and 25 ducts between the cylinders; a piston in each cylinder, one piston of each pair being coupled to a piston of the other pair and positively actuated in opposite cycles; the other pistons of each pair being engaged in common by a single compression spring 30 tending to force each piston into its cylinder.
  2. In a hydraulic pump, the combination of two pairs of cylinders, in axial alignment, each cylinder of a pair communicating at its inner end with its mate and with an inlet 35 and an outlet valve and ducts between the cylinders; a piston in each cylinder, one piston of each pair being coupled to a piston of the other pair and positively actuated in opposite cycles, the other pistons of each 40 pair being engaged in common by a single compression spring tending to force each piston into its cylinder.
  3. As in claim 1, with adjustable means to impart and retain any desired tension to the 45 compression spring.

Signed at Atlanta, Georgia, this 16th day of August, 1920.

NELSON B. HENRY.
